BAR SCREEN SCRAPER

Robert E. Briggs, Columbus, Ohio, assignor to
The Jeffrey Manufacturing Company, a corpora-
tion of Ohio

Application August 16, 1934, Serial No. 740,159

14 Claims. (Cl. 210—176)

This invention relates to apparatus for removing solid refuse or trash from a stream of water, such as a sewage stream, preliminary to the passing of said water to settling tanks.

One object of the invention is to provide in the above mentioned class of apparatus a rake or scraper which is adapted to operate to clean the screen of said apparatus efficiently.

Another and important object of the invention is to provide for an interleaving of the teeth of a rake or scraper and the screen bars of a screen of the above mentioned type at a position in advance of an area on said screen at which refuse tends to collect or pile up.

Another object of the invention is to provide in an apparatus of the class above described, a rake for cleaning the screen bars of a screen and spring cam means for urging the rake teeth in interleaving relation with said screen bars adjacent the bottom of the screen where refuse tends to collect, for the purpose of yieldingly maintaining said interleaving relation.

Other objects of the invention will appear hereinafter, the novel features and combinations being set forth in the appended claims.

In the drawings:

Fig. 1 is a front elevational view of the device embodying my invention, illustrating the associated tank or trough in section;

Fig. 2 is a side elevational view of the device in Fig. 1, illustrating the several floor levels in section;

Fig. 3 is an enlarged detail view showing the construction of my device adjacent the refuse collecting or bottom portion thereof and taken along the line 3—3 of Fig. 4, looking in the direction of the arrows;

Fig. 4 is a sectional view taken along the line 4—4 of Fig. 3, looking in the direction of the arrows; and

Fig. 5 is an enlarged perspective view of the lower portion of my invention showing the rake or scraper interleaved with the extension of the screen.

The invention here involved relates primarily to an improvement in the material handling apparatus disclosed in my co-pending application, Serial No. 701,548 filed December 8, 1933.

Referring particularly to Figs. 1 and 2 of the drawings, the apparatus comprises a screen A adapted to be partially submerged in a tank or trough into which the liquid, such as sewage, is to pass before entering a settling tank. The guide tracks B are provided with draft chains carrying the rake or scraper C, which tracks B are adapted

to be mounted upon the supporting frame D. Also carried upon said frame D is a driving means E for driving of said rake or scraper C.

The screen A is formed by a pair of spaced side plates 10, 10 which are adapted to be fixed to the side walls of the concrete tank or trough 11 into which the screen A projects, by lugs 10' which project inwardly thereof and fit into vertical slots 11' extending upwardly from the bottom of plates 10, 10. Said lugs may be threaded to 10 receive nuts 13'. Between the side plates 10, 10, and perpendicular thereto, extend the lateral spacing and supporting bars 12 which may be welded to said side plates 10, 10 at their ends and thereby be rigidly attached thereto. Also between said side plates 10, 10, and parallel therewith, extend a plurality of screen bars 13 having spaced downward extensions 12' (Fig. 3) carried upon said lateral bars 12 and rigidly attached thereto, as by welding. Each of said screen bars 13 preferably comprises an upstanding plate spaced apart from the next spaced screen bar whereby a screen is formed. Said bars 12 not only give rigidity to the screen bars but also keep them properly spaced when, as for example, a 25 large piece of material between two of them tends to spread them apart and move them adjacent the next bars. Said bars 12 therefore maintain the screen bars 13 in proper spaced relation to provide proper alignment thereof for the ready 30 passage of the teeth of the rake or scraper therethrough and prevent increased friction between the rake or scraper teeth and said screen bars.

Adjacent the bottom wall of the tank or trough 11 and set with its upper face in alignment with the upper face of said lower wall is a plate 14. Said plate is held rigid in the concrete forming the bottom wall of tank or trough 11 by adhesion of the lower face of said plate with the adjacent concrete. The screen bars 13 of the screen A, 40 through which the raw refuse-containing fluid as received from a sewer is adapted to flow, as indicated by the arrows in Fig. 2, are extended from an inclined position where they form said screen to a substantially horizontal position above the 45 plate 14 where they form extensions 15. The said extensions 15 are welded adjacent their bottom edges to the top of said plate 14 whereby they are prevented from spreading, thus being maintained in proper alignment to receive the 50 teeth of the rake or scraper C. Said plate also holds the extensions down against any tendency thereof to move upwardly.

The side plates 10, 10, which are of greater depth than the screen bars 13 adjacent the 55

screen portion A, are reduced in depth adjacent said plate 14 to a depth equal of said screen bars 13. Said side plates 10, 10 are also welded adjacent their bottom edges to said plate 14. Said extensions 15 and the side plates 10, 10 preferably project beyond the end of the plate 14 and are tapered at 16 to meet the bottom wall of the tank or through guide and to guide the refuse from the refuse laden stream on to the screen A. Brackets 15' are provided to extend over the two side screen bar extensions and are attached to the side wall of the tank or trough 11. These brackets 15' prevent any tendency for the extensions 15 to pull the plate 14 from its anchorage with the bottom of said tank or trough 11.

The upper portion of said screen A is rigidly attached to the concrete supporting floor 17 of said tank or trough by the channel member 17' welded to said screen A and buried in said floor 17, and is formed rigid with the curve plate 18, as by welding. Said plate 18 is carried by the frame D and has a discharge lip 19 for discharging refuse on the floor 17, or, if desired, on a conveyor belt or into refuse receptacles or a grinder. If the refuse is discharged on the floor 17 the liquid portion and small particles thereof may return to the sewer stream through drain 18' in floor 17.

The curved guide tracks B are formed by a pair of spaced angle members 20, 20 which are bent upon themselves to form a substantially U-shaped guide track for the continuous rake or scraper carrying draft chains 21, 21. Said angle members 20, 20 are mounted upon the face plates 22, 22, as by welding. The open side of the guide channels formed by said angle members 20, 20 are provided with the welded retainer plates 23, 23 to retain said chains 21, 21 in their tracks. Said tracks B are mounted and supported on the frame D and, if desired, may be attached at intervals to the side walls of the tank or trough 11.

The continuous chains 21, 21 are adapted to be driven by sprockets 24, 24 mounted on the shaft 25 carried in suitable bearings upon the frame D. Said shaft 25 is adapted to be driven from the motor 26 by driving means E, through the speed reduction device 27 and the sprocket and chain means 28. A chain tensioning device 29 may be provided for said sprocket and chain 50 device 28.

Also carried upon the frame D is a scraper cleaning mechanism comprising a transverse bar 30 carried on the arms 31, 31 pivoted to said frame D at 32 and weighted by the counter-weight 33 on the lever 34 to maintain said cross bar 30 in wiping contact with the rake or scraper C during the movement thereof past the discharge lip 19. The frame D may also be provided with a ladder 35 to provide ready access to the driving mechanism E.

The construction of the rake or scraper C is best illustrated in Figs. 3, 4 and 5 and comprises a central angle member 36 carried between the laterally-spaced brackets 37, 37 having the arms 38, 38 pivoted to the oppositely-disposed, inwardly-projecting bolts 39, 39 extending through journal bearings 40, 40 on said arms 38, 38, said bolts 39, 39 being carried upon the oppositely-disposed plates 41, 41, which plates are carried by the extended link bolts 42, 42 of the chains 21, 21. The link bolts 42, 42 are each provided with a pair of spaced nuts 43, 43 for adjustably positioning the plates 41, 41. Said plates 41, 41 are provided with inwardly-projecting stop lugs 44, 44 to limit the movement of the arms 38, 38 about

their pivot points 39, 39 in one direction of movement and with the lugs 45, 45 to limit the pivotal movement of said arms 38, 38 in another direction of movement. The brackets 31, 37 are preferably made integral with the arms 38, 38 and are attached to the angle member 36 as by the bolts and nuts 46, 46. Rigidly attached to the angle member 36 is a rake or scraper plate 47 provided with the lateral shoulders 48, 48 extending to each side of the angle member 36 and provided adjacent the bottom thereof with the projecting teeth 49. As best illustrated in Fig. 4, said teeth 49 have appreciable length and in normal operation are intended to project completely through the screen bars 13 of the screen A. Said teeth 49, however, are shorter than the side plates 10, 10 thus allowing for the lateral bars 12 to be attached to the projections 12' on the screen bars 13 and to said side plates 10, 10 and yet provide clearance of said teeth 49 when they are fully interleaved with the screen bars.

Also carried by the angle member 36 and rigidly attached thereto, as by welding, is a reinforcing weighting bar 50, the principal function of which is to add weight to said rake or scraper C to maintain the above mentioned interleaving relation when said rake or scraper is carrying refuse during its upward movement.

The guide tracks B are preferably provided with the cam members 51 which are adapted to lift the rake C, as it reaches its downward position, from the pins 45, 45 upon which the arms 38, 38 thereof normally rest during the downward travel of said rake or scraper C, to a position adjacent the projecting stop lugs 44, 44. Said cams 51 rotate said rake or scraper C by virtue of engagement of the lateral shoulders 48, 48 with the upper portion of said cams 51. The cams 51 are terminated when the gravitational force on the rake or scraper C is effective to draw the arms 38, 38 against the stop lugs 44, 44 rather than tending to move said arms 38, 38 towards the stop lugs 45, 45. By virtue of this arrangement a shock, otherwise incident to the rotation of the rake or scraper C about the axes 39, 39 as the arms 38, 38 of said scraper C move from stops 45, 45 to stops 44, 44 incident to the moving of the chains 21, 21 around the lower bend of the guide tracks B, is effectively prevented.

It is to be particularly noted that due to the horizontal extensions 15 of the screen bars 13, 13, the interleaving of said bars and the teeth 49 of the rake or scraper C takes place at a position appreciably in advance of the area on said screen A at which refuse or solid matter tends to accumulate. The concentrated area of accumulation will be adjacent the curved portion of said screen A designated by the character G in Figs. 2, 3 and 5. By virtue of the above mentioned interleaving of said teeth 49 and the screen bars 13 in advance of the area of concentration of refuse, it has been discovered that prior tendencies for the teeth 49 to ride over the screen A without proper interleaving, due to the riding of the rake or scraper C upon refuse or foreign matter accumulated on said screen A, are greatly reduced and a much more efficient cleaning of the screen A is effected during each travel of the rake or scraper C thereacross. As illustrated by the dotted line representations of the rake or scraper C, in Fig. 3, the teeth 49 thereof first begin to interleave with the extensions 15 at an upstream position well in advance of the area of accumulation G, and slightly downstream of

the brackets 15' whereby the rake or scraper teeth clear said brackets 15' yet are fully interleaved with the extensions 15 before reaching the accumulated refuse area. The position at which 5 the first interleaving takes place is indicated by the dotted line representation of the rake or scraper C at the left of Fig. 3 and a full interleaved position with the tips of teeth 49 riding on the plate 14 is illustrated in the second dotted 10 line representation of said rake or scraper. A position of the rake or scraper C intermediate the positions indicated by the dotted line representations of Fig. 3 is seen in Fig. 5 at which position the teeth tips are just coming into contact 15 with the plate 14.

The elongated construction of the teeth 49 whereby they project rearwardly beyond the screen bars 13 is also effective to clean said screen A efficiently, for any refuse or foreign matter 20 that may be caught between the screen bars 13 will be effectively drawn out by said rake or scraper C which, as may be noted from Fig. 3, forms an obtuse angle with said screen bars 13.

It has been discovered, however, that sometimes due to a heavy accumulation of refuse at 25 the area G or to the accumulation of large pieces of fibrous material at said area, there may be a tendency for the teeth of said rake or scraper C to be disengaged from their interleaving relation with said screen bars 13. To prevent this disengagement except under conditions of unusual load as, for example, when a large piece of solid matter like a rock or brick is found on said screen A, the leaf-spring cams 52, 52 are provided 30 and carried on the lower angle members 20, 20 of the guide tracks B to maintain yieldingly the interleaving relation of said teeth 49 and said screen bars 13. Said cams 52, 52 are adjustably attached to the bottoms of the guide tracks B as 35 by the brackets 53, 53 provided with the elongated slots 54 through which extend fastening bolts provided with nuts. By loosening the nuts of said bolts, the position of said bracket 53 may be adjusted and thereby adjust the position of the cam 52 relative to said screen A. The forward 40 end of the cam 52 is looped back on itself to form a U and provides a bearing surface 55 adapted to bear against the lower face of said lower angle member 20 and to be freely movable with respect thereto.

In normal operation when the rake or scraper C is in proper interleaving relation with the screen bars 13 of the screen A, the lateral shoulders 48, 48 of said screen A do not come in contact with the lower surface of said cams 52, 52. 45 However, should the accumulated refuse at said area G, or at any area along said screen A opposite the cams 52, 52, tend to disengage said teeth 49 from said screen bars 13, said cams 52, 52 will be effective to maintain yieldingly this interleaving relation. However, said interleaving relation is not positively maintained by said cams 52, 52 and, should a large particle of material require the disengagement thereof to prevent damage 50 to the rake or scraper C, said cams 52, 52 will yield and allow said disengagement.

The combination of the screen A with the horizontally-extending projections on the screen bars 13 and the cooperating leaf-spring cams 52, 52 is very effective to provide and maintain a proper interleaving of the teeth 49 of the said rake or scraper C with the screen bars 13 of the screen A to remove effectively any refuse or solid matter accumulated on said screen A or lodged 55 between the screen bars 13 thereof and yet pro-

vide for the disengagement of said rake or scraper C from said screen A should said disengagement become necessary to prevent damage to the rake or scraper or to the screen A.

In the operation of my device, the driving mechanism is effective to drive the draft chains 21, 21 in the guide tracks B, either continuously, intermittently, as by the means disclosed in my above mentioned application, or at the will of an operator, as by manual control. The chains 21, 21 and guide tracks B carry the rake or scraper C downwardly along the upper portion of the guide tracks B, with the arms 38, 38 of said rake or scraper C resting against stop lugs 45, 45. As the rake or scraper C reaches cams 51, 51 the 15 shoulders 48, 48 thereof ride upon the top surface of said cams 51, 51 and arms 38, 38 are pivoted about pivots 39, 39 in their movement toward stop lugs 44, 44. Cams 51, 51 terminate when said rake or scraper C has reached a position in which the force of gravity acting thereon is effective to maintain arms 38, 38 adjacent said stop lugs 44, 44. Cams 51, 51, thus prevent any shock to chains 21, 21 incident to the movement of rake or scraper C from a position where arms 20 38, 38 rest against stop lugs 45, 45 to a position where they rest against stop lugs 44, 44.

As the rake or scraper C moves downwardly around the lower curved surface of the guide tracks B, the teeth 49 thereof interleave with 30 the extensions 15 of the screen bars 13 forming screen A. This interleaving takes place at a position well in advance of the area G on said screen at which the greater amount of solid matter tends to accumulate, thus providing for the 35 proper interleaving of the rake or scraper teeth before they are called upon to do any work, and at a position where there is little possibility of any accumulated refuse which might prevent said interleaving. In normal operation the weight 40 of the rake or scraper C is effective to maintain the interleaved relation thereof with the screen bars of the screen even when there is a large accumulation of refuse on said screen A, particularly at area G. However, if this accumulation is 45 very heavy, or is of a particular kind of material, such as fibrous material, it may tend to disengage said teeth from said screen bars. Leaf-spring cams 52, 52 are effective upon a slight lifting of the rake or scraper C from the screen 50 A, to contact the shoulders 48, 48 of said rake or scraper to maintain yieldingly said interleaved relation, but are adapted to yield and allow actual disengagement of the teeth from said screen bars should some extreme condition require such action to prevent damage to the rake or scraper or 55 to any other part of the device.

As the rake or scraper C moves upwardly along the screen A, the teeth 49 project entirely through the screen bars 13 of the screen A and thus pull out any material caught between adjacent bars, as well as removing any refuse accumulated on the surface of said screen.

As the rake or scraper C approaches the curved plate 18, it is tilted about its axes 39, 39 by the engagement of teeth 49 with a plate at the top 65 of said screen A whereby the teeth 49 disengage the screen bars 13 and slide across the curved plate 18 with their lower ends in sliding contact therewith, carrying the refuse before it. The 70 refuse is then discharged at the lip 19 to some device, not shown, such as a traveling belt conveyor, receptacle or grinder, or on the floor 17.

Incident to the discharge of said refuse, the rake or scraper cleaner bar 30 wipes across the 75

face of the rake or scraper and removes downwardly any refuse which tends to adhere thereto. The rake or scraper C is then carried around sprocket wheels 24, 24 and again moved down 5 the upper track of the guide tracks B.

While only one particular arrangement of the frame D, screen A and guide tracks B, has been illustrated and described in this particular application to which my improved construction has 10 been applied, it is obvious that the spring leaf cams may be applied to any of the guide tracks disclosed in my above mentioned co-pending application and that the extensions 15 of the screen bars may be applied to any of the screens disclosed in said application.

While in the preferred form the horizontal extensions 15 of the screen bars 13 are formed by bending each screen bar adjacent the area G and thus forming each screen bar 13 from a single 20 bar of material, said extensions may be formed by the welding of the horizontal portions thereof to the upwardly-inclined portions thereof adjacent the area G. This latter construction may 25 particularly be employed when the screen A has been previously constructed without the horizontal extensions 15 of the screen bars 13.

In the construction of the device, the screen A is fabricated with the plate 14 and channel bar 17' welded thereto. In building the tank or 30 trough 11 and the floor 17, excavations are provided to receive said plate 14 and channel bar 17. Threaded lugs 10' are anchored integral with the side walls of said trough or tank when it is constructed. The screen A is lowered vertically 35 into place with the notches 11' registering with the lugs 10'. The extensions 15 project beyond the plate 14 at 16 and at this point may rest on the bottom of the tank or trough adjacent an edge of the excavation which is below the plate 40 14. This extension at 16 thus helps properly place the screen while grout is poured into the excavation below plate 14 to fill it and anchor said plate 14 to the bottom of said tank or trough. The floor 17 being excavated to receive the channel 45 17' is also filled with grout to anchor said channel, after the screen A is in place.

As this application is for an improvement of the material handling apparatus disclosed in my co-pending application Serial No. 701,548 filed 50 December 8, 1933, the claims are, in general, restricted to features not shown or described in said co-pending application. It is to be distinctly understood, however, that the patentable subject matter disclosed but not claimed in this application is not dedicated to the public but is claimed 55 in said co-pending application. Purely as illustrative, and not as exhaustive, it may be stated the claims of said co-pending application cover the general construction of the guide tracks 60 herein disclosed, the general relation of said guide tracks to the screen, the rake cleaning mechanism, the shock preventing cams mounted on the guide tracks, the combination of the screen with a floor plate, the particular discharge plate construction for the screen, the lateral spacing and 65 supporting bars for the screen bars, the particular mounting of the rake on the conveyor chains, as well as numerous other structural details and combinations of elements not herein specifically 70 claimed.

Obviously those skilled in the art may make various changes in the details and arrangement of parts without departing from the spirit and scope of the invention as defined by the claims 75 hereto appended, and I wish therefore not to be

restricted to the precise construction herein disclosed.

Having thus described and shown an embodiment of my invention, what I desire to secure by Letters Patent of the United States is:

1. In a liquid screening apparatus, the combination with a screen having screen bars through which refuse carrying liquid is to be passed, a pivoted scraper provided with teeth adapted to interleave with said bars as said scraper moves 10 relatively to said screen, and stationary yieldable cam means to maintain yieldingly said interleaved relation.

2. In a liquid screening apparatus, the combination with a screen having upwardly-extending 15 screen bars through which refuse carrying liquid is to be passed, spaced draft guides adjacent the edges of said screen on the up-stream side thereof, draft means carried in said draft guides, a toothed scraper carried between said draft means, and cam means adapted to maintain an interleaving relation between the teeth of said scraper and said screen bars as said scraper moves upwardly along the face of said screen, said cam means comprising spring leaves attached 25 to said draft guides.

3. In a liquid screening apparatus, the combination with a screen having upwardly-extending 30 screen bars through which refuse carrying liquid is to be passed, spaced draft guides adjacent the edges of said screen on the up-stream side thereof, draft means carried in said draft guides, a toothed scraper carried between said draft means, and cam means adapted to maintain an interleaving relation between the teeth 35 of said scraper and said screen bars as said scraper moves upwardly along the face of said screen, said cam means comprising spring leaves attached at one end thereof to said draft guides.

4. In a liquid screening apparatus, the combination with a screen having upwardly-extending 40 screen bars through which refuse carrying liquid is to be passed, spaced draft guides adjacent the edges of said screen on the up-stream side thereof, draft means carried in said draft guides, a toothed scraper carried between said draft means, and cam means adapted to maintain an interleaving relation between the teeth of 45 said scraper and said screen bars as said scraper moves upwardly along the face of said screen, 50 said cam means comprising spring leaves attached at one end thereof to said draft guides and loosely bearing against said guides at their ends.

5. In a liquid screening apparatus, the combination with a screen having upwardly-extending 55 screen bars through which refuse carrying liquid is to be passed, spaced draft guides adjacent the edges of said screen on the up-stream side thereof, draft means carried in said draft guides, a toothed scraper carried between said draft means, and cam means adapted to maintain an interleaving relation between the teeth of said scraper and said screen bars as said scraper moves upwardly along the face of said screen, said cam 60 means comprising curved spring leaves adjustably attached to said draft guides.

6. In a liquid screening apparatus, the combination with a toothed scraper, of means for guiding said scraper, draft means for moving said 70 scraper, a screen having screen bars adapted to be interleaved with the scraper teeth, said bars having a non-screening substantially horizontal portion and a rectilinear inclined portion, means preventing a flow of liquid through said 75

non-screening portion, said scraper being guided by said guide means to interleave said teeth with the horizontal portion of said screen bars as said scraper is moved across said screen.

5. 7. In a liquid screening apparatus, the combination with a toothed scraper, of means for guiding said scraper, draft means for moving said scraper, a screen having screen bars forming a screening area and adapted to be interleaved with the scraper teeth, said screen bars extending beyond said screening area and approaching a horizontal non-screening position, said scraper being guided by said guide means to interleave said scraper teeth and screen bars adjacent the horizontal position of said bars, and stationary yieldable cam means adapted to maintain said interleaved relation.

8. In a liquid screening apparatus, the combination with a screen through which refuse carrying liquid is to be passed, spaced scraper guides positioned adjacent said screen, a pivoted scraper carried by said guides and adapted to move over said screen to remove the accumulated refuse, and yielding cams carried by said guides adapted yieldingly to maintain said scraper in refuse removing relation with said screen.

9. A screen adapted to remove refuse from a refuse carrying fluid comprising spaced screen bars each having an upwardly inclined screening portion, a substantially horizontal non-screening portion constructed and arranged to form a guide for a rake, means constructed to prevent a flow of fluid through said non-screening portion, and a smooth concave curved portion connecting the inclined portion and the horizontal portion and forming a refuse accumulating area.

10. In a liquid screening apparatus, the combination with a trough, of a screen adapted to remove refuse from liquid passing through said trough, a portion of said screen being rectilinearly inclined upwardly through said trough and another portion being parallel with the bottom of said trough and being attached to a plate parallel therewith, a rake adapted to interleave with both portions of said screen, and means for moving said rake relative to said screen.

11. In a liquid screening apparatus, the combination with a screen, of a rake adapted to be moved with respect thereto, draft means for mov-

ing said rake, and cam means adapted to maintain said rake in operative relation with said screen, said cam means being adjustably mounted at one end by a bracket having a pair of elongated slots, and bolts extending through said slots and into said guide means.

12. In a liquid screening apparatus, the combination with a screen, of a rake adapted to be moved with respect thereto, draft means for said rake, and cam means adapted to maintain said rake in operative relation with said screen, said cam means being rigidly secured at one end and non-rigidly secured at the other end, said non-rigidly secured end having sliding contact with a surface.

13. In a liquid screening apparatus, the combination with a screen formed by rectilinear upwardly extending screen bars through which refuse carrying liquid is to be passed, of horizontal extensions on at least some of said screen bars adjacent the bottoms thereof which form a concave upper surface forming a refuse accumulation area beyond which said extensions project upstream, a rake having teeth adapted to interleave with said bars, guide means for said rake whereby said interleaving begins with said extensions upstream of said refuse accumulation area, said rake teeth having sufficient length to extend through said bars, and a plate positioned below said extensions for sufficient distance that the rake teeth ride on the top surface thereof until said refuse accumulation area is reached whereupon they project through said screen.

14. In a liquid screening apparatus, the combination with a screen formed by rectilinear upwardly extending screen bars through which refuse carrying liquid is to be passed, of horizontal extensions on at least some of said screen bars adjacent the bottoms thereof which form a concave upper surface forming a refuse accumulation area beyond which said extensions project upstream, means preventing a flow of liquid between said horizontal extension, a rake having teeth adapted to interleave with said bars, guide means for said rake whereby said interleaving begins with said extensions upstream of said refuse accumulation area.

ROBERT E. BRIGGS.
